ARTHUR MUTSCHELLER, OF NEW YORK, N. Y., ASSIGNOR TO WAPPLER ELECTRIC CO., INC., A CORPORATION OF NEW YORK.

THERAPY X-RAY SYSTEM.

Application filed January 23, 1923. Serial No. 614,358.

My invention relates to therapy X-ray systems, the purpose being to improve the qualities of the X-rays produced, in order to obtain the most economical operating conditions and to obtain a maximum of efficiency in the rays as applied to deeply located portions of the human body. The principal object in thus modifying the quality of the rays is to reduce to a minimum the undesirable effects resulting from the necessary exposure of the skin and superficial tissues of the body, in order to deliver to deep seated parts of the body such a dose of X-rays as is capable of stopping malignant growths and thus assisting nature in healing disease.

In the practical development of X-ray apparatus for radiographic as well as for therapeutic purposes, it has become the custom to use a high tension transformer with its secondary windings connected to a synchronous rectifying mechanism. The rectifying mechanism usually comprises stationary contact brushes or segments and a synchronously-operated revoluble member of insulating material provided with sectors of conducting material. These sectors co-act with the stationary brushes or segments, and are so arranged as to reverse the direction of the flow, through a portion of a circuit including with an X-ray tube, of every second impulse, or second half, of the alternating current cycle.

In connection with X-ray apparatus heretofore used for radiographic purposes, it has been found that a rather heterogeneous radiation is best suited for the purpose of producing radiographic plates having the maximum contrast and clearness. Following this idea, the X-ray machines for radiographic purposes have been constructed and operated so that the radiation produced in the tube is not of uniform penetrative power, but consists of a mixture of rays of various degrees of penetration.

In modern therapy X-ray apparatus, relatively much higher voltages are produced than in radiographic apparatus, the purpose being to obtain greater transmission values and a greater ratio between the surface and depth doses. However, to accomplish this end it was necessary to pass the radiation through metal filters with the intent of selectively absorbing in the filter all those rays

which do not possess the normal degree of penetrative power. This filtering process actually does improve the homogeneity of the rays.

The thickness of the filter required, however, depends on the degree of homogeneity required, and upon the voltage applied to the tube. Thus if the radiation is very highly heterogeneous, a thicker filter is required than when the radiation is more nearly homogeneous. Moreover, for the older types of apparatus, the filter thickness must be varied and adapted for every different voltage applied to the tube; so that the problem of exactly matching the correct filter thickness to the given conditions is by no means a simple one. As a rule it requires considerable skill and costly apparatus to determine correctly the proper thickness of filter.

On the other hand, when thick filters are necessary for the purpose indicated, the diminution of the total intensity of the radiation is considerable; and the immediate result of this is a proportionate inefficiency in the utilization of energy, resulting in waste such that comparatively long periods of treatment become necessary, and the lifetime of the X-ray tubes and apparatus is considerably shortened; whereby the cost of treatment is considerably augmented.

It is evident that if a large portion of the X-rays emitted from an X-ray tube must be absorbed in the filter, because of not possessing the normal degree of penetrative power, then in order to obtain a certain depth dose there is much more heating and wearing of the target of the tube, and the extent of this heating and wearing increases in the same proportion as the heterogeneity of the rays increases. Furthermore, it is generally found, with X-ray apparatus of the type which produce a rather heterogeneous radiation, not only that the life of the tube is short, but that the maximum voltage which can safely be applied to the tube is very limited. As is well known, the application of higher voltages to the tube results in a larger X-ray output, greater penetration of the rays and greater scattering. Thus, while for instance doubling of the milliamperes causes only doubling of the X-ray intensity, doubling of the voltage causes approximately four times the inten-

sity of X-ray radiation, in addition to increased penetrability and greater scattering of the rays.

Since the work here contemplated requires the production of as nearly homogeneous a radiation as possible, and since it is definitely known that the degree of penetration depends on the voltage of the current applied to the tube, it can be inferred that the contact sectors carried by the synchronized rectifying mechanism as above mentioned could be so positioned and so shaped that the best possible results, as regards potential and wave form of the high tension current supplied to the X-ray tube, are obtained. Hitherto the result desired, namely, the high potential current and a uniformity of voltage during the time each impulse lasts, as against other undesirable developments, was always in the nature of a compromise. When short sectors are used in the rectifying mechanism, it is of course necessary that the current be interrupted while a high voltage impulse is applied to the rectifier, and considerable arcing therefore does take place. Incidental to this arcing, there are developed a number of undesirable manifestations in connection with the X-ray tube, such as sputtering at the tube, terminals, and danger of puncturing, flickering of the tube and decreased efficiency in X-ray output. These undesirable developments are probably due to the formation of oscillations in the secondary circuit, incidental to the sparking at the rectifier. It is quite obvious that the sectors carried by the rectifier mechanism should make contact with the stationary brushes only during the moments of maximum voltage of the current impulses, and that the contact should be interrupted whenever a lower voltage part of the impulse begins. I have made the discovery that the arcuate length of the sector should be such that the voltage value, during the time of contact, is practically constant. In other words the sector should be shortened just so far, and so far only, that no portion of the current impulse is collected, the voltage of which is essentially less than the maximum voltage of the impulse. Therefore contact should exist only during the time when the crest of the potential curve runs nearly parallel with the base line associated with the curve, and that contact should be interrupted just before and just after this point is reached.

When using for this purpose ordinary commercial alternating current in connection with the apparatus above contemplated, the best arcuate length for the sector is from 16 to 22 degrees; that is, assuming that the entire cycle of alternating current extends through 180 degrees, and is of sinewave form; that is, if the one wave or half cycle

be considered as extending from 90 degrees then the arcuate length of the sector is 16 to 22 degrees. If the current wave is differently shaped, as for instance if it has clearly defined peak formations, a shorter segment would become necessary. On the other hand if the alternating current impulse is more nearly flat the length of the segment can be increased. The principal point is, that only current approximately uniform in voltage should be applied to the tube, and all varying portions of the current impulse should be prevented by the rectifier from passing through the tube. If the sector has a greater arcuate length than that necessary for the purpose just mentioned, it picks out a portion of the curve with lower potential, and the radiation from the tube as a consequence be more heterogeneous, so that the radiation produced by the lower voltage part of the current curve must be eliminated by passing the radiation through comparatively thick filters. On the other hand if the arcuate length of the sectors is less than that above indicated, the X-rays produced are of good homogeneous quality, but the operation of the apparatus is rendered inefficient, because of not directing all the normal and useful parts of the curve through the tube.

This method of adapting the arcuate length of the contact sectors of the rectifier mechanism to the wave form produced in the transformer is accompanied by difficulties which heretofore have rendered impracticable the application of this principle. In particular, the interrupting of the impulse causes arcing in the rectifier, and generally causes the formation of oscillations in the circuit.

The electrical factors involved in an oscillating system dealing with damped oscillations are inductance, capacity and resistance; the resistance being that of the spark gap, properly balanced and arranged. In the problem now under discussion, variation of the capacity factor appears to have a very important influence.

I have discovered that reduction of the capacity of the secondary circuit to the lowest practical minimum eliminates oscillations almost completely, and as a result there is a more steady and uniform performance by the tube so that, other things being equal, higher voltages may be applied to the tube. Following the same reasoning further, I have discovered that by placing damping resistances in the secondary circuit and by locating them relatively near the places where the sparking occurs, that is, in that portion of the circuit in close proximity to the rectifier, I can still further increase the smoothness of operation, the limits for the voltages, and the efficiency of X-ray production.

To state this principle more clearly it may be assumed that in a given machine the sectors make contact with the brushes at the moment when the electric impulse 5 starts, and maintain this contact until the impulse has completely passed. Then a considerable amount of capacity, if present in the high tension circuit, does not cause oscillations to be set up, and may not have 10 any considerable effect upon the operation of the machine, because arcing at the rectifier is not taking place. In this case, therefore, the introduction of resistance into the secondary circuit will have little or no beneficial effect. Assuming however, that the 15 sectors are made a little shorter so as to leave off a small part at the beginning and end of the current impulse, then there might be a certain amount of arcing at the rectifier: 20 and in order to avoid the formation of oscillations the capacity of the secondary circuit must be made smaller, or else a certain amount of damping resistance corresponding to the capacity in the circuit must 25 be placed in the secondary circuit.

Again, assuming that the capacity of the secondary circuit could be made very small, so as to approximate zero value, then little or no damping resistance would be necessary 30 to prevent the formation of oscillations.

Continuing the same method of reasoning, if the sectors are made so short as to pick out only those portions of the high tension electric impulse during which the potential 35 is ordinarily constant, so as to obtain the nearest approximation to the conditions above described as required for producing homogeneous X-rays, it is necessary to observe very closely the relation between the 40 capacity and resistance. The capacity should always be made as small as possible, and since in practice it can never be reduced sufficiently to attain a zero value, it becomes necessary to introduce a sufficient 45 amount of damping resistance to annul the remaining unavoidable capacity effects. If for any reason it is necessary to leave in the secondary circuit any capacity in excess of the minimum attainable in practice, it 50 becomes also necessary to balance this additional capacity by adding considerably more damping resistance in the secondary circuit.

Practically speaking, in a circuit of the kind here contemplated, the shorter the sectors are made the greater becomes the chance 55 for arcing at the rectifier, and therefore the greater becomes the tendency to set up oscillations in the secondary circuit. Theoretically, a very large amount of capacity might 60 be left in the circuit and its effect could be nullified by placing in the circuit an adequate amount of damping resistance to prevent the development of oscillations by discharges from the capacities. In practice this 65 is not usually done, however, for the reason

that excessive damping resistance, such as would be required, would act as ballast resistance and would thus decrease the efficiency of the apparatus.

It may be understood from the foregoing 70 remarks that, as a rule, it is better to reduce the electrical capacity of the secondary circuit as low as is feasible from the mechanical standpoint, and then to annul the capacity still remaining by including in the 75 circuit an appropriate amount of damping resistance.

I find it good practice, therefore, to design the apparatus with a view to its withstanding very heavy potential strains; and to 80 give the sectors each an arcuate length of about sixteen to twenty-two degrees. I also find it advisable, in doing this, to maintain the static capacity of the secondary circuit as low as practicable; and in addition, to 85 introduce in the circuit a sufficient amount of damping resistance to balance or annul the residual capacity effect. I find that by doing this I prevent the formation of oscillations, surges and excessive arcing at the 90 rectifier, and that the X-rays produced are much more homogeneous and of greater penetrating power, or, in general, that the efficiency of the apparatus as a whole is relatively much higher.

In connection with the device described in the foregoing, and with reference to the penetrative power of the rays, I have discovered another point of advantage. In the present art the use of sphere gaps for measuring high tension voltages has been found to give, for practical purposes and with the older types of X-ray apparatus, the most reliable and uniform results. The sphere gaps employed at present are standardized 100 by the American Institute of Electrical Engineers, the voltages being given as root mean square voltages for corresponding 105 sparking distances between the spheres. The penetrative power of the X-rays produced however, is a function of peak voltage of the current applied to the tube, and as a rule the readings of the sphere gap are translated into peak values by multiplying the tables published by the American 110 Institute of Electrical Engineers by the well known factor $\sqrt{2}$. This factor is correct, provided the curve is a true sine wave or nearly a complete sine wave. But when 115 only correcting the central portion of the curve and giving it therefore, more the shape of a vertically standing rectangle and the impulses are well spaced apart, the corresponding root mean square voltage values are very much smaller than in the case of 120 the sine wave. Conversely, the voltages measured with the sphere gap as now used and as calibrated according to the specifications of the American Institute of Electrical Engineers, to be converted into true 125 130

peak voltages, must be multiplied by a larger conversion factor than the one usually employed.

I find that in measuring the voltage of an X-ray machine constructed according to my principle, with the sphere gap usually employed, greater depth values are obtained than with other machines of the older construction and with voltages measured with sphere gaps in a similar way. Therefore, not only does a machine constructed according to my principle furnish a current of a type in which the X-ray tube will tolerate a considerably higher voltage as measured with the sphere gap than the machines of the older construction, but the radiation emitted from an apparatus of the kind contemplated by my improved construction will have greater penetrative power than that produced by a machine of the older construction, if operated with the same voltage as measured with the sphere gap.

A still further advantage arises from my improved construction. As above stated, the thickness of the filter required for use in the older type machines must be matched to correspond to the various voltages, and therefore a different filter thickness must be employed for each particular voltage. I have found that with my apparatus this is not necessary, because of the fact that no low voltage part of the current curve is collected by the rectifier, and hence the purpose of the filter is only to eliminate the stray radiation coming from the stem of the electrodes, the glass wall of the X-ray tubes, etc., and radiation of this kind is generally much less penetrating than the principal radiation, and therefore effectively removed with a comparatively thin filter. Hence with my device it is not only possible to homogenize the radiation sufficiently for therapeutic purposes by the use of a much thinner filter, but it is not necessary to vary the filter thickness to adapt it for the various voltages with which the machine can be operated. The filter thickness, if once determined for any convenient voltage, will be the same for all other voltages, and hence due to the correct shape of the curve form and not dependent upon the voltage applied to the tube. This eliminates one factor which in the prior art has been a source of much uncertainty. Many difficulties are eliminated as the result of my device.

My invention admits of such universal application as not to be limited to any particular apparatus. However, as an example I illustrate and describe a typical form of X-ray machine embodying the principles here contemplated.

Reference is made to the accompanying drawing forming a part of this specification, and in which like reference characters in-

dicate like parts throughout all of the figures.

Figure 1 is a diagram of an X-ray apparatus made in accordance with my invention, and intended for use in deep therapy by means of X-rays of great penetrative power and relatively high homogeneity.

Figure 2 is a diagram showing a conventional curve and appropriate legends for indicating the manner in which the potential peaks of the current impulse are ordinarily picked out.

A pair of high tension transformers are shown at 4 and 5, and are respectively provided with primary windings 6 and 7 and secondary windings 8 and 9. A pair of mains 10 and 11 are connected with the primary windings 67 for the purpose of energizing them.

Another transformer is shown at 12, and is provided with a primary winding 13 and a secondary winding 14. The primary winding 13 is connected with conductors 15 and 16, energized either from the mains 10 and 11 or in any other appropriate manner. The transformer 12 is for the purpose of supplying currents for heating the glower cathode, as hereinafter described.

An X-ray tube is shown at 17, and is provided with a glower cathode 18 and an anode 19.

A synchronous motor 20 is used for actuating the various movable parts. Two conductors 21 and 22 lead from this motor to the mains 10 and 11. The motor 20 is provided with a revoluble shaft 23, carrying upon its ends two rectifying disks 24 and 25, which are moved synchronously with reference to the alternating currents used. Each disk 24, 25, carries sectors 26, 27, 28 and 29, in this instance four in number. Each disk also carries two conductors 30 and 31, serving as connectors. Adjacent each disk 24, 25 are stationary brushes, 32, 33, 34 and 35. From the brush 32 of the disk 24 a wire 36 leads to the anode 19 of the X-ray tube.

Two wires 37 and 38 are connected with the secondary winding 8 of the transformer 4, and are also connected with a pair of damping resistances 39 and 40. A wire 41 leads from the resistance 39 to the brush 33 of the disk 24, and a wire 42 leads from the resistance 40 to the brush 34 of this disk. Similarly two wires 43, 44, are connected with the secondary winding 9 of the transformer 5, these wires also being connected with a pair of damping resistances 45 and 46. From the resistance 45 a wire 47 leads to the brush 33 of the disk 25, and from the resistance 46 a wire 48 leads to the brush 34 of this disk.

From the secondary winding 14 of the heating transformer 12 a wire 49 leads to the glower cathode 18 of the X-ray tube. A

wire 50 is also connected with this cathode, and with a wire 51, the wire last mentioned leading to the brush 32 of the disk 25. A wire 52 is connected with wires 50 and 51, 5 and leads therefrom to the secondary winding 14 of the heating transformer.

From the brush 35 of the disk 24 a wire 53 leads to a damping resistance 55, and a similar wire 54 leads from the brush 35 of the disk 25 to a damping resistance 56. The two damping resistances 55 and 56 are by means of a wire 57 connected to the ground at 58.

The circuits here used are of the kinds 15 conventionally employed. However, for the sake of clearness I will describe one of the secondary circuits employed for energizing the X-ray tube, this circuit being incidental to the apparatus with the movable parts 20 thereof occupying the positions indicated for them in Figure 1.

The just mentioned circuit may be traced as follows: secondary winding 8 of transformer 4, wire 37, damping resistance 39, 25 wire 41, adjacent brush 33, sector 27, conductor 30, sector 26 and brush 32 of disk 24, wire 36, anode 19, cathode 18, wire 50, wire 51, adjacent brush 32, sector 36, conductor 30, sector 27 and brush 33 of disk 25, 30 wire 47, damping resistance 45, wire 43, secondary winding of transformer 5, wire 44, damping resistance 46, wire 48, adjacent brush 34, sector 28, conductor 31, sector 29 and brush 35 of disk 25, wire 54, damping 35 resistance 56, 55, (grounded through wire 57), wire 53, adjacent brush 35, sector 29, conductor 31, sector 28 and brush 34 of disk 24, wire 42, damping resistance 40 and wire 38, back to secondary winding 8 of transformer 40 4.

The damping resistances 39, 40, 45, 46, 55 and 56, may each be made of any sort of high resistance material. They may be either rod resistances, liquid resistances, 45 powder resistances or resistances of almost any kind suitable for the purpose, but preferably they should not be inductive resistances. I find it a good idea to distribute the damping resistances throughout the circuit as shown, rather than to merge them 50 into a single resistance unit, or to place them all in substantially the same part of the circuit. The damping resistances are 100,000 to 150,000 ohms each.

In the apparatus just described, and particularly in the circuit just traced and others of its kind, I seek to reduce to a minimum the static capacity of the various parts, as 55 above described. That is to say, I do away with all condensers, reduce the amount of metallic surface exposed by the various parts, and even shorten up the wires and other conductors as much as practicable. The smaller the total static capacity of the 60 secondary circuit used for energizing the X-

ray tube, the shorter the sectors 26, 27, 28 and 29 can be made without increasing the total damping resistance of the circuit, and the shorter the sectors are made the better will be the penetration of the X-rays, other 70 factors being equal. As above explained however, it is on the other hand desirable to operate the X-ray tube at its maximum efficiency, and this calls for lengthening the sectors to the maximum extent possible without unduly reducing the potential and correspondingly increasing the amperage. 75

If the foregoing principles be not strictly observed, and particularly if the secondary circuits are permitted to have too much 80 static capacity for the arcuate length of the sectors, or inversely if the sectors are too short for the total static capacity of the circuit, oscillations and undesirable arcs are set up and the efficiency of the X-ray tube, 85 and of the apparatus as a whole, is greatly reduced. However, if the sectors be each made of proper length to cause the X-ray tube to send off rays of sufficient intensity and adequate penetration, and the static 90 capacity of the circuit be reduced as far as practicable, and it still be found that oscillations or undesirable arcing takes place, the damping resistances are added or increased, 95 as the case may be, to an extent proper to 95 balance the circuit and prevent the evils mentioned. For obvious reasons the total amount of damping resistance added must be kept down to a minimum, as otherwise the excessive resistance must impair the efficiency of the apparatus in another way. 100

In the diagram shown in Figure 2, the curve represents a complete circle of the alternating current, and the letters, *a*, *b*, *c*, *d*, *e*, *f*, *g*, represent sub-divisions of the curve. 105 Manifestly the best part of the high tension current, for the purpose here contemplated, is that part located between the letters *b* and *c*. The part of the curve extending from *a* to *g* may in many instances be used to advantage, although the mean potential for this part of the curve is somewhat lower than that of the part of the curve between *b* and *c*, and the X-rays thus produced are therefore 110 not quite so desirable from the standpoint of quality. The part of the current represented by those portions of the curve between *d* and *a* and between *g* and *f* are considered as worthless, or worse than worthless, and it is desirable that they be cut out, 115 by shortening the sectors as above described.

I do not limit myself to the precise mechanism shown, as variations may be made therein without departing from my invention, the scope of which is commensurate 120 with my claims.

I claim:

1. In a device of the character described, the combination, with an X-ray tube and a circuit connected therewith, of mechanism 125

- included in said circuit for supplying to said circuit a succession of high potential intermittent currents each having its potential substantially uniform throughout the period 5 of duration of the current impulse, said circuit having small static capacity and including a damping resistance quantitatively correlated to said small capacity, and co-acting therewith for preventing oscillations.
- 10 2. In a device of the character described the combination, with an X-ray tube and a circuit connected with said X-ray tube and having small static capacity, of mechanism connected with said circuit for supplying 15 thereto high tension currents each of short duration and having its potential approximately uniform, and a measure of ohmic resistance included in said circuit and so apportioned relatively to the total static capacity 20 of the circuit as to balance said capacity and thus prevent oscillations from being set up in said circuit.
3. The combination of an X-ray tube, a high tension transformer provided with a 25 secondary winding for energizing said tube, a rectifying switch provided with revoluble contact sectors for picking out potential peaks each of substantially uniform voltage from the current impulses generated by said 30 secondary winding, means for synchronizing said rectifying switch, and a circuit including said X-ray tube, said secondary winding and said rectifying switch, said circuit also including damping resistance adequate 35 to balance the effect of the static capacity of said circuit in order to prevent oscillations from being set up in said circuit.
4. The combination of a vacuum tube, a high tension transformer provided with a secondary winding for energizing said vacuum tube, means for generating high tension current impulses, an electric switch for selectively picking out from each current impulse a portion of the current impulse having high potential and also having its potential substantially uniform throughout the portion thus picked out, a circuit including 45 said vacuum tube and also including said secondary winding and said electric switch, said circuit having relatively small static capacity and having a total ohmic resistance adequate to so balance said static capacity as to prevent the production of oscillations 50 in said circuit.
5. The combination of an X-ray tube, means for generating a succession of current impulses, switch mechanism for selectively picking out predetermined portions of each 60 of said impulses and supplying the portions thus picked out to said X-ray tube, and mechanism in circuit with said X-ray tube and with said secondary winding and said switch mechanism for balancing the capacity effect of the circuit. 65
6. In a system of the character described, the combination of a vacuum tube, a transformer provided with a secondary winding for energizing said vacuum tube, switch mechanism for picking out a predetermined portion of each electric impulse generated by said secondary winding and supplying to said vacuum tube said predetermined portion thus picked out, a circuit including said vacuum tube and also including said secondary winding and said switch mechanism, and a damping resistance included in said circuit and so apportioned as to balance the static capacity of said circuit. 70
7. In a system of the character described 75 the combination of an X-ray tube, a transformer provided with a secondary winding for supplying current impulses to said X-ray tube, a synchronous motor, an electric switch connected with said synchronous motor and driven synchronously thereby, said switch being provided with a stationary contact brush and with a revoluble contact sector associated with stationary contact brush, said revoluble sector having a relatively 80 short arcuate length for the purpose of picking out the peaks of high potential from the current impulses generated in said secondary winding and thus supplying said 85 peaks of high potential to said X-ray tube, a circuit including said X-ray tube, said secondary winding and said electric switch, and means included in said circuit for balancing the static capacity thereof. 90
8. In a system of the character described 100 the combination of a vacuum tube, a high tension transformer provided with a secondary winding for generating current impulses of momentary duration, a circuit including said vacuum tube and said secondary winding, a synchronously driven switch included in said circuit and provided with means for selectively picking out and supplying to said vacuum tube portions of said current impulses, each as nearly as practicable uniform in potential throughout the length of the portion thus picked out, and mechanism included in said circuit for balancing the static capacity inherent in the circuit. 105
9. In a system of the character described 110 the combination, with an X-ray tube, of a transformer provided with a secondary winding for energizing the tube, a rectifying switch for rectifying current impulses generated by said secondary winding, said switch being provided with a stationary contact brush and with a revoluble member disposed adjacent said contact brush and carrying a sector associated with said brush, said sector having an angular length of 115 sixteen to twenty-two degrees for picking out the peak portions of the current impulses and supplying the portions thus picked out to the X-ray tube, and a circuit including 120 said X-ray tube, said secondary winding and 125 said switch mechanism. 130

said switch, said circuit having an added resistance to balance the total static capacity of the circuit and thus to prevent the formation of oscillations therein.

- 5 10. In a system of the character described the combination of a vacuum tube, a transformer for producing current impulses to energize said vacuum tube, a revolvable rectifying switch operated synchronously with said transformer for the purpose of rectifying said current impulses as supplied to said vacuum tube, said rectifying switch being provided with revolvable sectors each having an angular length not ex-

ceeding sixteen to twenty-two degrees for the purpose of picking out the portions of high potential of said current impulses, and a circuit including said vacuum tube, said transformer and said rectifying switch, said circuit including also a damping resistance added thereto for the purpose of preventing oscillations from developing in said circuit.

Signed at Long Island City, N. Y., in the county of Queens and State of New York, 25 this 20 day of January, 1923.

ARTHUR MUTSCHELLER.
